DESIGN FOR A VANITY CASE

August Most and Joseph Fogel, Brooklyn, N. Y.

Application September 24, 1937, Serial No. 71,771

Term of patent 7 years

To all whom it may concern:

Be it known that we, August Most and Joseph Fogel, both citizens of the United States and residents of the city of New York (Borough of Brooklyn), in the county of Kings and State of New York, have invented the new, original, and ornamental Design for a Vanity Case, of which the following is a specification, reference being had to the accompanying drawing forming part thereof, in which

In the drawing the surface ornamentations on the top and bottom of the vanity case are indicated in broken lines. The dominant feature of the design resides in the portions shown in full lines.

We claim:

The ornamental design for a vanity case, as shown and described.

AUGUST MOST.
JOSEPH FOGEL.
